DESIGN FOR A PENCIL SHARPENER

Eugene Weiss, New York, N. Y.

Application September 13, 1938, Serial No. 79,862

Term of patent 3½ years

To all whom it may concern:

Be it known that I, Eugene Weiss, a citizen of the United States, residing at New York city, in the county of New York and State of New York, have invented a new, original, and ornamental Design for a Pencil Sharpener, of which the following is a specification, reference being had to the accompany drawing, forming a part thereof.

Fig. 1 is a front perspective view of a pencil sharpener, showing my new design.

Fig. 2 is an end elevational view of the same.

Fig. 3 is a rear elevational view of the same Fig.

1.

Fig. 4 is a similar view to Fig. 1, with the cover plate removed.

I claim:

The ornamental design for a pencil sharpener, as shown and described.

EUGENE WEISS.
